(57) **CLAIM**

The ornamental design for a accessory mounting track as shown and described.

DESCRIPTION

FIG. 1 is a front perspective view of an accessory mounting track.

FIG. 2 is a front elevational view of the accessory mounting track shown in FIG. 1.

FIG. 3 is a rear elevational view of the accessory mounting track shown in FIG. 1.

FIG. 4 is a top plan view of the stretcher accessory mounting track in FIG. 1.

FIG. 5 is a bottom plan view of the stretcher accessory mounting track in FIG. 1.

FIG. 6 is a right side elevational view of the accessory mounting track shown in FIG. 1; and,

FIG. 7 is a left side elevational view of the accessory mounting track shown in FIG. 1.

The area between the broken lines along a longitudinal center of the accessory mounting track in FIGS. 1–5 forms no part of the claimed design so as to reflect that the accessory mounting track is an indeterminant length.
